Primary Examiner — Shawn T Gingrich*(74) Attorney, Agent, or Firm* — JK Intellectual Property Law, PA(57) **CLAIM**

The ornamental design for a power and audio adapter box, as shown and described.

DESCRIPTION

FIG. 1 is an isometric, upper front view of the power and audio adapter box according to the present design;

FIG. 2 is a bottom view thereof;

FIG. 3 is a rear view thereof;

FIG. 4 is a top view thereof;

FIG. 5 is a front view thereof;

FIG. 6 is a right side view thereof;

FIG. 7 is a left side view thereof; and,

FIG. 8 is an isometric, upper front view thereof, showing locations of connector sockets to be attached to openings in the front surface and a gland on a side surface of the box. Broken lines in FIGS. 1–8 indicate the bounds of the claimed design and unclaimed subject matter. Elements shown in broken lines form no part of the claimed design.

1 Claim, 7 Drawing Sheets(56)
